FREQUENCY CHANGER

Application filed May 24, 1928, Serial No. 280,354, and in France May 30, 1927.

It is known that electric oscillations may be produced by means of a vacuum tube the grid and plate circuits of which are suitably coupled and have proper electric characteristics. The oscillations are maintained by the variations of the resistance of the space between the plate and the filament under the influence of the varying potential of the grid with reference to the filament.

These variations of resistance are in proper phase when the alternating voltage between the filament and the grid is in phase opposition with that between the plate and the filament.

It is also known that chiefly in the neutrodyne devices, the reaction due to the alternating voltage appearing in the impedance of the plate circuit may be compensated by setting up in the grid circuit a voltage having a phase in opposition to that in the plate circuit.

It is therefore necessary in a great number of cases to provide in the plate and grid circuits of the usual vacuum tubes, voltages almost exactly in phase opposition. This result is difficult to obtain and requires delicate adjustments, complicated connections and causes unavoidably an increased expense of energy. Moreover a mere variation in the phase of the voltage between the grid and the filament causes the oscillating state of the generating tubes to vary suddenly whereby the said tubes are submitted to mechanical stresses and may break.

My invention has for its object electron discharge tubes and connections devised therefor which remove the drawbacks disclosed hereinabove. It consists in controlling the modifications in the resistance of the space between the plate and the filament no more by means of a grid disposed between the said plate and filament but through an auxiliary conductor disposed on the side of the filament opposed to the plate whereby the variations in the potential of this conductor cause variations in the plate current which are opposed to those which would arise through the same variations in the potential of a grid disposed between the filament and the plate.

In other words, the plate current decreases when the controlling conductor is brought to positive increasing voltages with reference to the filament whereas the plate current increases when the control conductor is brought to negative increasing voltages. This is due to the fact that owing to the relative position of the electrodes, the electrons near the filament move away from the control conductor as they move towards the plate.

It is obvious that such an electron discharge tube allows the oscillations to be maintained, the voltages to be amplified, the successive amplifications to be neutrodyned, etc. I obtain this result by means of connections which also form part of the invention and which are characterized by the fact that the control conductor is connected without any auxiliary circuits, with a point of the oscillating plate circuit, or in a simpler manner directly with the plate.

The control conductor may be connected with the filament through resistances or choking coils and in its connection with the plate a condenser may be inserted if it is necessary to avoid this control conductor from being given the constant potential applied to the plate.

I have described hereinbelow by way of example with reference to the accompanying drawing a form of execution of my invention.

The figure is a wiring diagram wherein the tube according to the invention acts as a frequency changer. This figure shows a tube with a grid built according to the invention and adapted to serve in an autodyne receiver which may be used as a frequency changer according to the superheterodyne method.

The anode and the control conductor may be constituted by plates parallel to the filament.

The control conductor 6 might be given a great variety of shapes, such as that of a grid or plate. It might also appear as a plurality of grids on the side of the filament opposed to the plate.

Due to the fall of potential in the circuit 11, the point 12 and consequently the controlling

- conductor 6 will be at a potential below that of the filament 2. Therefore the conductor 6 will repel the electrons and have a tendency to increase the plate current. As this current increases the fall of potential across the circuit 11 will also increase and thereby the difference of potential between the filament and the conductor 6 and the repulsive action of the conductor 6 will become greater.
- 10 The control conductor has thus the effect of increasing the variations of the plate current so that the oscillations are excited and reach rapidly a steady regimen.
- 15 The wireless waves are received by the aerial 13 consisting for instance in a frame shunted by an adjustable condenser 7 and inserted between the filament 2 and the grid 10. It is tuned to the frequency of the incoming waves.
- 20 The auxiliary conductor 6 and the filament are connected through the battery 5 and the oscillating circuit 11 tuned to the frequency $F-F'$. The device 8 is adapted to receive the currents at the secondary frequency $F-F'$;
- 25 consequently the control conductor 6, the plate 4 and the circuit connecting them form a generator of oscillations at the frequency F' , which interfere with the incoming oscillations at the frequency F so as to produce oscillations at the secondary frequency $F-F'$.
- 30 The latter oscillations are then received in the receiver 8 which may be an amplifier, a telephone or the like.

What I claim is:

- 35 A frequency changer comprising a vacuum tube inside which are included a cathode emitting electrons, on one side of said cathode an anode and a grid between cathode and anode, on the other side a controlling electrode whose
- 40 distance from the cathode is much smaller than that of the anode, a circuit receiving the waves whose frequency F is to be changed connected on one hand to the cathode and on the other to the grid, an oscillatory circuit
- 45 whose natural frequency F' differs from F by the predetermined frequency f into which the frequency F must be changed, said oscillatory circuit being connected on one hand to the cathode and on the other hand simultaneously to the controlling electrode and to the negative pole of a battery whose positive pole is connected to the anode, between said oscillatory circuit and the anode a receiving device adapted to work at the frequency
- 50 $f=F-F'$ of the beats produced.
- 55

In testimony whereof I have affixed my signature.

LUCIEN LEVY.
